UNITED STATES PATENT OFFICE.

SHAD SHANTON JONES, OF WICHITA, KANSAS.

SWINGING COUCH.

1,201,305.

Specification of Letters Patent. Patented Oct. 17, 1916.

Application filed January 21, 1915. Serial No. 3,579.

To all whom it may concern:

Be it known that I, SHAD S. JONES, citizen of the United States, residing at Wichita, in the county of Sedgwick and State of Kansas, have invented certain new and useful Improvements in Swinging Couches, of which the following is a specification.

My invention is designed as an improved portable swinging couch.

10 The objects of the invention will appear as the description proceeds.

In describing my invention in detail reference will be had to the accompanying drawings wherein like characters denote like 15 or corresponding parts throughout the several views, and in which:—

Figure 1 is a perspective view of the improved couch; Fig. 2 is a side elevation illustrating the arrangement of the couch in such 20 relation to its supporting frame as to be utilized as a canopy or top, a swing being suspended between the frame sides or uprights in a space ordinarily occupied by the couch; Fig. 3 is a detail perspective view of 25 one of the uprights or standards forming a part of the frame; Fig. 4 is a detail perspective view illustrating the manner in which the hanger bars are affixed to the frame; and Fig. 5 is an end view of the couch frame 30 illustrating its application as a swinging bed.

Referring now to the drawings by numerals, 1 and 2 designate the respective uprights or standards between which the couch 35 designated as an entirety by the numeral 3 is arranged. As shown to advantage in Fig. 1, each standard is cut away to fit a recess therefor formed in the legs or supports designated respectively 4 and 5, the said supports being provided with casters or rollers 6, and being connected or braced by means of a beam 7 enlarged at each end to engage the adjacent faces of the respective supports. The beam 7 is longitudinally grooved as indicated at 8, a groove being formed at each 45 side of the beam within which groove brace or connecting rods 9 are fitted, the said rods extending throughout the length of the beam and passing through openings therefor in the respective supports and through openings in the respective uprights 1 and 2, the openings of the uprights being alined with the openings of the supports in order that the beams, the supports and the uprights may 55 be so interlocked or fastened together as to

provide a substantial and rigid frame. Displacement of the rods 8 is prevented by the attaching block 10, the latter being engageable with the outer face of the uprights or standards 1 as shown. Each upright is made 60 smaller in cross section at a point adjacent its free end as indicated at 11, the said portion being hereinafter termed an extension. Canopy supports 12, each provided with a socket (not shown) fit over and upon the respective extensions 11, the uprights or standards serving as the support means for the respective canopy supports. Preferably, the canopy supports extend outwardly or at an angle to the standards 1 in order that the 70 canopy designated as an entirety by the numeral 13 may be of such size as to effectually shade the swinging couch arranged therebeneath. The canopy top is braced against lateral displacement through the medium of 75 brace cords 14 and 15, the respective cords being made fast at one end to the canopy and at their opposite end to the canopy support. If desired, additional brace cords 16 may be provided, the said cords extending 80 vertically from the support 4 to the canopy top.

Couch 3 is suspended over and above the beam 7 and between the uprights 1 and 2 by means of hanger bars 17, each bar being 85 slotted at a point designated 18, through which slots the supporting pins 19 extend, the said pins being carried by the respective uprights, nuts 20 being utilized to removably fasten the hanger bars in place. When thus suspended, it is evident that the couch 3 may be swung back and forth beneath the canopy top after the fashion of a swing. If desired, the couch may be fastened to the uprights by a latch as indicated at 21, thus 90 precluding swinging movement. The said couch 3 consists of a suitable frame, designated as an entirety by the numeral 22, the frame being made up of a plurality of connecting frame sections designated respectively 23, 24, 25 and 26, the end sections 25 and 26 forming the head and foot respectively of the couch. Frame sections 24 and 23 are pivoted as at 27 to the respective end sections 25 and 26, such connection providing for movement of the couch frame sections into various positions. A suitable spring 28 is arranged within the frame 22, the spring being fastened as indicated at 29 to the respective sections 23 and 24 and to 110

the end sections 25 and 26 as indicated at 30, the connection at 30 being made possible by the provision of a plurality of helical springs fastened at one end to the said end 5 frame section and at their opposite end to the spring 28.

As shown in Fig. 1, the frame sections are so arranged as to provide a couch or settee, the end sections 25 and 26 forming 10 respectively the head and foot of the couch, the frame section 23 forming the back of the couch and the frame section 24 being hung to depend and to form a leg rest. In Fig. 5 I have shown the sections so arranged 15 as to form a bed or horizontally flat support, the respective frame sections 23 and 24 being extended in line with the base of the end sections, suitable brace means, such as chains as are indicated at 31 providing 20 for the retention of the said side section in the manner described. As shown, the spring 28 and the frame 22 are covered with suitable material such as leather or plush in order that the couch may be occupied 25 with comfort. When used as a bed, the hanger bars 17 are locked against swinging movement by the means designated 21.

If required, the canopy top 13 may be removed by first disengaging the brace cords 30 16 and bodily lifting the canopy until entirely removed from engagement with its support.

Upon reference to Fig. 2 it will be noted that a swing or hammock 31 has been suspended 35 from the uprights 1 and 2 to occupy the space ordinarily occupied by the couch 3, this arrangement being made possible by elevating the couch in the manner shown, and locking the same to the canopy support 40 as indicated at 32. Hanger bars 17, when the couch is elevated in the position shown in Fig. 2, are moved in the path of a circle, the pins 19 acting as pivots and also as a retaining means whereby the hammock or 45 swing 31 is held in place. The canopy top 13 may or may not be used when the couch is elevated, as the occupant of the hammock or swing desires. It is however thought that the use of the canopy 13 is unnecessary 50 in view of the fact that the couch, when

thus positioned, acts in the capacity of a canopy or shade.

From the foregoing, taken in connection with the accompanying drawings it is evident that the couch may be so moved relatively to its supporting frame as to be utilized, if desired, as a canopy top; that the entire supporting frame may be collapsed or knocked down when not in use; and that the device may be used either within or without the house, and as a bed, couch or swing as occasion demands.

In reduction to practice, I have found that the form of my invention, illustrated in the drawings and referred to in the above 65 description, as the preferred embodiment, is the most efficient and practical; yet realizing that the conditions concurrent with the adoption of my device will necessarily vary, I desire to emphasize the fact that 70 various minor changes in details of construction, proportion and arrangement of parts may be resorted to, when required, without sacrificing any of the advantages of my invention, as defined in the appended 75 claims.

Having thus fully described my invention, what I claim as new and desire to secure by Letters Patent, is:—

1. A convertible couch, a suitable support 80 therefor, means for suspending the couch from said support, the said couch being movable to a position serving as a canopy top, and a means on the support to retain the couch in a canopy-serving position. 85

2. The combination with a support, of a couch, a means suspending the couch for swinging movement from said support, the couch being movable in the path of a circle to a position serving as a canopy top, and a 90 means connected with said support and fastened to the couch to retain the latter in a canopy-serving position.

In testimony whereof I affix my signature in presence of two witnesses.

SHAD SHANTON JONES.
